UNITED STATES PATENT OFFICE.

HOWARD M. JOHNSTON, OF TORONTO, ONTARIO, CANADA, ASSIGNOR TO MASSEY-HARRIS COMPANY, LIMITED, OF TORONTO, CANADA.

ENDLESS CARRIER.

1,418,577.

Specification of Letters Patent. Patented June 6, 1922.

Application filed July 31, 1920. Serial No. 400,499.

To all whom it may concern:

Be it known that I, HOWARD M. JOHNSTON, of the city of Toronto, in the county of York, Province of Ontario, Canada, a subject of the King of Great Britain, have invented certain new and useful Improvements in Endless Carriers, of which the following is a specification.

This invention relates particularly to the means for carrying the canvas conveyors employed in harvester binders. When such machines are not in use it is desirable that the conveyors should be slackened to take the tension off the canvas, and my object is to provide means for supporting one or more of the rollers carrying such conveyors in such a manner that the conveyors may be rapidly and easily tightened and slackened as required.

20 I attain my object by means of the constructions hereinafter described and illustrated in the accompanying drawings in which—

Fig. 1 is a rear elevation of part of a harvester binder illustrating the location of the endless carriers to which the invention is applied;

Fig. 2 a plan view, partly in section and partly broken away, of one of the rollers provided with my improvements;

Fig. 3 an end elevation of the same parts showing the rollers in the carrier tensioning position; and

Fig. 4 a similar view showing the roller in the carrier slackening position.

In the drawings like numerals of reference indicate corresponding parts in the different figures.

Referring particularly to Fig. 1, 1 is the grain deck conveyor and 2 and 3 the elevating conveyors of a harvester binder, these conveyors as usual comprising slotted canvas belts running on rollers 4. To one roller of each conveyor will be applied the means for tightening and slackening the conveyors herein described. Referring particularly to Figs. 2, 3 and 4, it will be seen that the roller 4 is formed of a shell sleeved on an end member 5 having a hub 6 which is journalled on a stationary shaft 8, which extends from end to end of the roller. In practice roller bearings will be used between the hub 6 and the shaft 8, but such construction is, of course, not essential to my invention. A disk 12 is provided with a hub 7 secured on

the shaft. This disk forms one member of a toggle, 9 being the other member of the toggle, which is pivoted at 10 on the frame of the machine. The hub 7 slides in a slot 11 in the frame, so that by straightening out 60 the toggle members to the position indicated in Fig. 3, the roller will be moved to tension the carrier, which by swinging the toggle members to the position shown in Fig. 4, the roller will be moved to slacken the canvas of the conveyor. The members 12 at each end of the roller are secured to the shaft 8 so that by rotating the shaft both members 12 will be rotated. To rotate the shaft I provide the handle 13. I find the most 70 convenient arrangement is to pivot this handle at 14 on the shaft so as to facilitate the engagement and disengagement of the other end of the lever from the spring clip 15 secured to the frame. Normally this lever is engaged with the clip as shown in Figs. 2 and 3. When it is desired to move the roller to slacken the conveyor, the lever is swung out of engagement with the clip and then pulled over to the position shown 80 in Fig. 4, the direction of rotation being as indicated by arrow in Fig. 4.

It will be noted that the toggle member or disk 12 is cut away to form a diametrically extending shoulder 16. This shoulder 85 engages the under side of the toggle member 9, when the parts are in the position shown in Fig. 3, just after the toggle members have reached their position of greatest extension, and thus prevent further movement 90 of the said members past that position. The strain of holding the toggle members in their extended position is thus taken off the lever 13. The opposite end of the shoulder 16 engages the upper side of the toggle member 95 9 when the toggle members have been operated to slacken the canvas and thus prevents further movement of the toggle members. To give sufficient relative movement of the toggle members and to provide for the proper engagement of the member 9 with the shoulder 16, I find it necessary to cut away the toggle member 9 as indicated at 17, thus maintaining the toggle member out of contact with the shaft 8. 105

What I claim as my invention is:—

1. An endless travelling carrier, including a roller round which the carrier passes and a supporting frame therefor, provided with a carrier slackening and tensioning device 110

comprising a shaft, on which said roller is journalled, slidable in the frame; disks secured one to each end of the shaft; and a link at each end pivoted to the frame and 5 said disk, the link and disk forming toggle mechanism normally holding said shaft in its carrier tensioning position.

2. A device constructed as set forth in claim 1 provided with a shoulder on each 10 disk engageable by the adjacent link just after the toggle members have reached their position of greatest extension to prevent further movement of said members past that position.

15 3. An endless travelling carrier, including a roller round which the carrier passes and a supporting frame therefor, provided with a carrier slackening and tensioning device

comprising a shaft, on which said roller is journalled, slidable in the frame, toggle 20 mechanism at each end of the shaft engaging the shaft and the frame normally holding said member in its carrier tensioning position; a lever arm pivotally connected to one end of the shaft to swing on an axis at right 25 angles to the shaft; and a clip secured to the frame and adapted to hold the lever when the members of the toggle mechanism are in their carrier tensioning position.

Signed at Toronto, Canada, this 14th day 30 of July, 1920.

HOWARD M. JOHNSTON.
